His Attorney

UNITED STATES PATENT OFFICE.

GEORGE S. LEDDICK, OF SCHENECTADY, NEW YORK, ASSIGNOR TO GENERAL ELECTRIC COMPANY, A CORPORATION OF NEW YORK.

ELECTRIC SWITCH.

Application filed January 2, 1923. Serial No. 610,097.

One of the objects of the invention is to provide an improved electric switch having a plurality of switch members and a common actuating means for the switch members, together with an interlocking arrangement between the switch members whereby operating the actuating means in one direction first imparts one relative movement to the switch members and then imparts a different relative movement to the switch members.

Another object of the invention is to provide an improved switch having at least two relatively movable switch members, one for controlling one circuit and the other for controlling another circuit, the one switch member being biased to the closed position but held in the open position by the other switch member by means of an interlocking connection which permits the one switch member to close and then reopen while the other switch member is being moved to the closed position, and then closed and reopened while the other switch member is being moved to the open position.

Another object of the invention is to provide an improved latching arrangement for holding the switch members in either of a plurality of predetermined relative positions and for limiting the speed of operation of the switch members. The arrangement for accomplishing this object of my invention is claimed in a divisional application, Serial No. 740,112, filed Sept. 26, 1924, patented May 4, 1926, No. 1,583,598.

These, and other objects of the invention as will be either explained fully hereinafter or as will be apparent to those skilled in the art, are attained in the electric switch which is shown on the accompanying drawing in which Figure 1 shows a plan view of the complete switch; Fig. 2 is a detail showing the latching arrangement; Figs. 3, 4 and 5 are simplified details showing the various relative positions of the relatively movable switch members of the switch and the interlocking arrangement between the switch members; and Fig. 6 is a simplified diagram of a control system in which the switch of the invention is used in the control of the field circuit of a synchronous motor.

Referring to the drawings, the electric switch comprises a switch member 10 and a pair of relatively movable switch members 11 and 11^a which are interlocked with the switch member 10 so as to control the

operation of the switch member 10. As shown in Figs. 3, 4 and 5, the switch member 10 is biased to the closed position; that is, in engagement with the stationary contact 12 by means of the coiled spring 13 which surrounds a post 14 which passes through the switch member 10 and the contact tip 15 thereof. The switch member 10 and the set of switch members 11 and 11^a are arranged to control separate circuits, and by an inspection of Fig. 6 it will be seen that the switch member 10 when in the closed position connects the field winding 16 of a synchronous motor in a local circuit which includes the resistor 17 so that the synchronous motor may be started as an induction motor until the speed thereof has increased to substantial synchronism. When the switch members 11 and 11^a are closed and the switch member 10 opened, the field winding of the synchronous motor is connected to the direct current supply circuit 18 so that the speed of the motor will be brought into synchronism with the alternating supply circuit 19 and the motor will operate as a synchronous motor. This is only one of the uses of my invention, and I can conceive that the invention may be applied to other uses in which it is desirable that the sequence of operation of a plurality of relatively movable switch members shall proceed in a definite order.

The switch members 11 and 11^a are mounted upon the shaft 20 which is mounted in the bearings 21 and 22, so that these switch members are pivotally supported for movement to and from their respective stationary switch contacts 23 and 24. By reference to Figs. 3, 4 and 5, it will be noted that there is an interlocking connection between the switch member 11 and the switch member 10 so that the switch member 10 is controlled in its movement by the switch member 11. In Fig. 4 the two switch members are shown in their relative positions when both switch members are in their respective open position. It will be seen that the bent strip 25, which is secured to the shaft 20 and also to the switch member 11, is in effect an extension of the switch member 11 and serves as a cam interlocking connection between the switch members 11 and 10. With the switch member 11 in the full open position, the upper end of the switch member 10 is engaged by the

- extension 25 at the apex 26 of the angle so that the switch member 10 is held in the open position against the bias of the spring 13 which tends to close the same.
- 5 When the switch member 11 is moved clockwise about its pivotal supports a limited distance as shown in Fig. 5, the upper end of the switch member 10 is permitted to move counter-clockwise by reason of the 10 action of the spring 13 so that the switch contact 15 will make engagement with the stationary contact 12 and connect the synchronous motor field in a local circuit including the resistor 17 (Figs. 5 and 6).
- 15 If the clockwise movement of the switch member 11 is continued, the upper end of the extension 25 will engage the upper end of the switch member 10 and will move the switch member 10 to the open position 20 against the action of the spring 13 until this opening movement is arrested by the stop 27. The switch member 11 will make engagement with its stationary contact 23 as shown in Fig. 3, thereby connecting the 25 field of the synchronous motor to the said direct current source of supply 18. It will be observed from the foregoing description that a continuous movement of the switch member 11 imparts one relative movement 30 to the switch members and then imparts a different relative movement; that is, moving the switch member 11 toward the closed position first permits the switch member 10 to move to the closed position and then 35 opens the switch member 10 before the switch member 11 is moved to the closed position. It will also be observed that in opening the switch, a continuous movement of the switch member 11 in the opening 40 direction first imparts one relative movement to the switch members and then a different relative movement; that is, in moving the switch member 11 from the closed position as shown in Fig. 3 towards the full open position as shown in Fig. 4, at 45 an intermediate position the switch member 10 will be permitted to close as shown in Fig. 5, and will be again returned to the open position when the switch member 11 has reached the full open position as shown 50 in Fig. 4. This has an advantage in that, for example, when the switch is used for controlling the field of a synchronous motor as shown in Fig. 6, when the motor field 55 is disconnected from the supply circuit it is connected in a local circuit so as to reduce the current in the field circuit preparatory to finally opening the motor field circuit.
- 60 For certain applications as, for example, in the control of the field circuit of a synchronous motor as shown in Fig. 6, it is desirable that the speed of operation of the switch members be limited, and for that 65 purpose I have provided the latching ar-

rangement shown in Figs. 1 and 2 which I shall now describe. I would have it understood that this latching arrangement is not limited in its application to the particular arrangement of relatively movable switch members which I have previously described, but that this feature of my invention is applicable generally where it is desired to limit the speed of operation of a plurality of switch members which are actuated by a common actuating means.

Referring to Figs. 1 and 2, the handle 28 which is connected with the shaft 20 provides a common actuating means for the switch members previously described. A latching arrangement is provided whereby this handle is held in either one of a plurality of predetermined positions and the speed of operation of this handle is limited. The 80 spring pressed detent 29 provides a locking member which is carried by and movable with the handle 28 and this detent cooperates with the stationary dial plate 30, which may be mounted on the casing of the switch, for holding the handle 28 in either one of a plurality of predetermined positions and for limiting the speed of operation of the handle. In the upper end of the handle there is provided an operating member for the detent 29. This member takes the form of a resiliently mounted push button 31 which is normally biased out of engagement with the dial plate 30 by means of the spring 32, but when this button is depressed as shown in Fig. 1, the left-hand end thereof engages the resilient detent 29 and moves the same out of engagement with the notched upper edge of the dial plate 30.

The operation of this part of my invention is as follows: In Fig. 2 the handle of the switch is shown as in the running position. In order to move the handle to the open position it is necessary to first press the button 31 so as to release the detent 29 from engagement with the notch in the upper edge of the dial plate 30. The handle may then be moved counter-clockwise until the left-hand edge of the detent 29 slides under the portion 33 of the dial plate 30. Further movement of the handle in the counter-clockwise direction is arrested because of the fact that the pin of the push button 31 is arrested at the left-hand end of the slot in the dial plate 30, so that the push button must be released to permit the handle to be moved until the detent 29 drops into the notch 34 and further movement of the handle in this direction is arrested. The relative positions of the switch members will now be as shown in Fig. 5. In order to continue the counter-clockwise movement of the handle, it will be necessary to press the push button 31 so as to thereby permit the detent 29 to slide under the portion 35 of the dial plate, and by moving the handle a

short distance counter-clockwise, the detent will be engaged under the portion 35. However, further movement of the handle is arrested until the push button 31 is released because of the fact that the end of the pin connected with the push button will engage the left-hand edge of the slot 36. When the push button has been released, the handle may be moved a short distance counter-clockwise until the detent 29 drops into the notch 37. Further movement of the handle counter-clockwise is thereby prevented. The relative positions of the switch members will now be as shown in Fig. 4.

15 In order to close the switch member 11, it will be necessary to press the push button 31, move the handle 28 a short distance clockwise until the pin associated with the push button 31 engages with the right-hand edge 20 of the slot 38, then release the push button out of engagement with the slot 38 so that the handle may be moved to the middle operative position at which the detent 29 will arrest further movement. In order to move 25 from the middle position to the final position, that shown in Fig. 2, it will be necessary to again press the push button 31, move the handle 28 a short distance clockwise until the detent 29 engages under the portion 30 33 of the dial plate, then release the push button and finally move the handle to the position shown in Fig. 2.

It will be observed that a definite sequence of operations must be had in order to move 35 the handle from one definite position to another definite position, and that this sequence of operations will limit the permissible speed of operation of the handle so as to thereby prevent the handle from being thrown 40 directly from one extreme position to the other. It will also be observed that the latching arrangement serves to positively hold the handle in either one of the predetermined definite positions of the handle so 45 that there is no possibility of unintentional operation of the switch members. The above described latching arrangement of Figs. 1 and 2 is claimed in my said divisional application on which my said Patent No. 1,583,598 50 issued on May 4, 1926.

In accordance with the provisions of the patent statutes, I have described the principle of operation of my invention, together with the apparatus which I now consider 55 to represent the best embodiment thereof, but I desire to have it understood that the apparatus shown is only illustrative and that the invention can be carried out by other means.

60 What I claim as new and desire to secure by Letters Patent of the United States, is:—

1. The combination in an electric switch

of two relatively movable switch members, means for biasing the first of the switch members to the closed position, a pivotal support for the second switch member, and a cam connected with the second switch member for holding the first switch member in the open position, releasing the same to close when the second switch member is moved toward a predetermined position, and then opening the first switch member before the second switch member reaches the said predetermined position.

2. The combination in an electric switch of two relatively movable switch members, means for biasing the first of the switch members to the closed position, and a pivotal support for the second of the switch members, the second of said switch members having an extension which engages the first switch member for holding the first switch member in the open position while the second switch member is in the open position, for releasing the first switch member to close when the second switch member is moved about the said pivotal support toward the closed position and for opening the first switch member prior to the closing of the second switch member.

3. The combination in an electric switch of two relatively movable switch members, a pivotal support for the first of said switch members, and connections whereby the first of said switch members while in the open position holds the second switch member in the open position against the bias of the same to the closed position, moving the first switch member toward the closed position first releases the second switch member to move to the closed position in accordance with its bias and then opens the second switch member before the movement of the first switch member to the closed position is completed.

4. The combination in an electric switch of two relatively movable switch members, means for biasing the first of the switch members to the closed position, a common actuating means for the switch members, and interlocking connections between the switch members whereby the first of said switch members is held in the open position against its bias by the second of said switch members, moving the second switch member toward the closed position first releases the first switch member to move to the closed position, and the first switch member is returned to the open position by a continuation of the movement of the second switch member to the closed position.

In witness whereof, I have hereunto set my hand this 29th day of December, 1922.

GEORGE S. LEDDICK.
